CLAIM

I claim the ornamental design for a tent, as shown and described.

DESCRIPTION

FIG. 1 is a right, front perspective view of my new design of a tent;

FIG. 2 is a right side perspective view thereof;

FIG. 3 is a left side perspective view thereof;

FIG. 4 is a top perspective view thereof;

FIG. 5 is a front perspective view thereof;

FIG. 6 is a rear perspective view thereof;

FIG. 7 is an enlarged, partial right side perspective view from detail area 7-7 of FIG. 2;

FIG. 8 is an enlarged, partial right side perspective view from detail area 8-8 of FIG. 2;

FIG. 9 is an enlarged, partial left side perspective view from detail area 9-9 of FIG. 3;

FIG. 10 is an enlarged, partial left side perspective view from detail area 10-10 of FIG. 3;

FIG. 11 is an enlarged, partial front perspective view from detail area 11-11 of FIG. 5;

FIG. 12 is an enlarged, partial front perspective view from detail area 12-12 of FIG. 5;

FIG. 13 is an enlarged, partial rear side perspective view from detail area 13-13 of FIG. 6; and,

FIG. 14 is an enlarged, partial rear side perspective view from detail area 14-14 of FIG. 6.

The evenly spaced dashed lines in FIGS. 2, 3, 5 and 6 indicate the boundaries of the detail areas and form no part of the claimed design.

1 Claim, 14 Drawing Sheets
